UNITED STATES PATENT OFFICE.

SAMUEL HOLMES, OF ELIZABETH, NEW JERSEY.

SYSTEM OF CONSTRUCTION FOR STEEL SHIPS.

1,076,208.

Specification of Letters Patent.

Patented Oct. 21, 1913.

Application filed July 1, 1912. Serial No. 706,950.

To all whom it may concern:

Be it known that I, SAMUEL HOLMES, a subject of the King of Great Britain, and residing at Elizabeth, in the county of Union and State of New Jersey, have invented certain new and useful Improvements in Systems of Construction for Steel Ships, of which the following is a specification; such as will enable those skilled in the art to which it appertains to make and use the same:

This invention relates to the construction of the hulls of steel ships, and particularly to the hulls of what are known as tank ships for transporting liquid cargoes such as, oil or other liquid material, and the object thereof is to provide a system of construction for the hulls of ships of this class which will simplify and render the said construction less expensive than at the present time, and which will also render said hulls more strong and durable, and with this and other objects in view the invention consists in the construction, combination and arrangement 25 of parts hereinafter described and claimed.

It is a well known fact that the hulls of vessels of the class specified are usually provided with transverse bulkheads and bulkhead frames by means of which the bulkheads are secured to the hull; and these bulkhead frames are usually composed of double angle irons; but in the case of tank ships the said frames are what are known as single angle iron frames riveted to the shell of the hull and to the bulkheads; and the edges of the angle irons are calked to produce oil tight joints; and the said hulls are also usually provided with central longitudinal bulkheads, and these bulkheads divide the hulls into separate compartments. These bulkhead frames and especially the transverse bulkhead frames are the worst features in the construction of a steel hull; they necessitate a direct line of rivet holes all around the hull in a transverse plane at each bulkhead and the rivet holes are made close together in order to produce water tight joints; but in the case of a tank ship in which the rivets are spaced three diameters apart, 44% of the shell of the hull is punched away and that in a direct line extending entirely around said hull at each bulkhead. This, of course, weakens the hull construction in the transverse plating of the bulkheads and this evil is increased by the fact that the bulkheads are made rigid

which fact directs all undue stresses to these parts, particularly the transverse sectional points in the plane of the bulkheads, all of which objections are remedied by means of my improvement, whereby the bulkheads are made elastic to a certain extent and the necessity of forming rivet holes so closely together in the shell of the hull and in transverse lines running around the hull, is obviated, and whereby there is a great saving of material in the bulkheads and the necessity of reinforcing the same is also obviated.

The invention is fully disclosed in the following specification of which the accompanying drawing forms a part, in which the separate parts of my invention are designated by suitable reference characters in each of the views, and in which;

Figure 1 is a transverse sectional view through a part of the hull of a tank ship constructed according to my improvement;—Fig. 2 a horizontal sectional view on the line 2—2 of Fig. 1; Fig. 3 a vertical sectional view on the line 3—3 of Fig. 1;—Fig. 4 a view similar to Fig. 3 but on an enlarged scale and showing the details of the construction;—Fig. 5 a fragmentary view of the outside shell of the hull and showing the line of rivets employed in securing the bulkheads in position;—Fig. 6 a modified form of the bulkhead construction;—Fig. 7 a view similar to Fig. 1 but showing the hull of an ordinary cargo vessel, instead of a tank ship;—Fig. 8 a section on the line 8—8 of Fig. 7;—Fig. 9 a section on the line 9—9 of Fig. 7;—Fig. 10 a view similar to Fig. 4 but taken on the line 10—10 at the bottom of Fig. 1, or at the top of said figure; and;—Fig. 11 a view similar to Fig. 2 but showing different forms of bulkhead construction.

In Figs. 1, 2, 3, 4, 5, 6 and 10 I have shown the hull construction which I employ in the case of tank ships, and in Figs. 5, 7, 8 and 9, I have shown the hull construction which I employ in the case of ordinary cargo ships, and in the first of these constructions I provide transverse bulkheads a and a central longitudinal bulkhead a^2 composed of sheet steel having vertical undulations forming reversely arranged trough-shaped members which open in opposite directions and which may be composed of separate parts which are riveted together, as shown at a^4 in Figs. 2, 3, 4 and 8, or instead of making said trough-shaped members separately they may be made with two, three or

more troughs or partial troughs in each part or section, as shown in Fig. 11, and instead of riveting said parts together, they may, if found practical, or advisable, be welded or otherwise secured together.

In Figs. 1, 2 and 7, I have shown a part of a hull of a ship of the class specified comprising one side wall or shell b , the bottom b^2 and the first or steel deck b^3 and the 10 side wall or shell b are composed of longitudinal strips or sheets of steel riveted together at b^4 in the usual manner, and at each side, only one side being shown, is an open space b^5 , as usual in this class of tank ships, 15 and said space or spaces are provided with a deck b^6 similar to the deck b^3 .

In practice the top end members of the transverse bulkheads are secured to the deck b^3 and to the bottom b^4 , of the hull, by angle 20 bars c bent to conform to the transverse undulations of said bulkheads, as shown in Fig. 4, and which are securely riveted both to the bulkhead members and to the deck b^3 and to the bottom of the hull, and the connection of the top of the bulkhead members with the deck b^6 are similarly made. The 25 sides of the bulkhead members are connected with the side or sides b of the hull, by means of vertically arranged bulkhead frames d having bottom gussets d^2 and made in the same manner as the bulkheads, except that the convolutions thereof are arranged horizontally, and said bulkhead frames are connected with the side or sides of the hull or shell thereof at d^3 by means of the angle bars c which are riveted thereto and to the side or sides of the hull in the same manner, as shown in Fig. 10, this construction being 30 clearly shown in Fig. 4, and the bulkheads 40 are connected with the bulkhead frames d at d^4 in the same manner, or by means of the angle bars c , which are riveted to said bulkhead frames and to the bulkheads, as shown at d^5 in Fig. 2, and in this construction I 45 preferably provide vertically arranged wing or web plates e which are riveted directly to the angle bar c and to which the bulkheads are riveted, as clearly shown in Fig. 2.

In connecting the transverse bulkheads a 50 with the longitudinal bulkhead a^2 , I provide vertically arranged web plates f which are riveted to the opposite side members of the transverse bulkheads, as shown at f^2 , and which divide the longitudinal bulkhead into 55 separate parts which are riveted thereto, as shown at f^3 .

Instead of forming the bulkheads a and a^2 and the bulkhead frames d on gradual curves or on semicircular curves in cross 60 section, as shown in Figs. 2, 3 and 8, they may be made V-shaped or angular in cross section, as shown at a^6 in Fig. 6, and be riveted together, as shown at a^6 , and the exact form of the undulations or trough-shaped members of the bulkheads and bulk-

head frames may be otherwise varied within certain limits and the radius of the curves on which the said undulations or trough-shaped members are formed is preferably twelve inches, but may, of course, be varied 70 according to the size of the ship and the dimensions and strength of the bulkheads desired, and this would make the greatest transverse dimensions of said bulkhead members approximately twenty-four inches. 75

In Fig. 5, I have shown a section of a side of the hull and at g the undulating line of the rivets by which the bulkhead frames and bulkheads are secured to the hull and this, as will be understood, avoids the necessity of 80 placing said rivets in a transverse line and the consequent weakening of the hull or shell thereof in the plane of the bulkheads, as hereinbefore set out.

In Figs. 7, 8 and 9, I have shown my improvement applied to an ordinary cargo ship having a steel hull, a false or tank bottom h , a top deck h^2 , and a main deck h^3 , and in the construction shown I employ ordinary bulkheads, or bulkheads of the usual construction, and which are placed between the decks h^2 and h^3 and between the deck h^3 and the false bottom h , as shown at i and i^2 , and these bulkheads are connected with the sides of the hull by bulkhead frames j similar in all respects to the bulkhead frames d , except that they are divided by the deck h^3 , in the form of construction shown, and are riveted to the deck h^2 and the deck h^3 , as shown at j^2 , and are connected with the false bottom h by a web member j^3 riveted thereto and to said false bottom. In this form of construction, the bulkheads are connected with the bulkhead frames j by wing or web plates k to which they are secured by means of angle irons k^2 riveted thereto and to said web plates, and the bulkhead frames j are secured to the hull b by means of the angle bars c riveted thereto and to said hull and the web plates, this construction being clearly shown in Fig. 9. 95 100 105 110 115

In Figs. 1 and 2, I have shown the shell of the ship as composed of separate plates riveted together and the connection between the hull and the angle bars c , the bulkheads and the bulkhead frames d as open, but it will be understood that these connections are all made tight in practice, as shown in Fig. 4, and the joints or connections between the separate bulkhead members, and between the transverse bulkheads and bulkhead frames, and between the bulkheads and the hull of the ships and the decks thereof are all made tight so that the liquid cargo cannot pass from one compartment of the ship to another. 120 125 130

It will be understood that the thickness of the material or steel sheets or plates, from which the bulkheads are formed, or the strength thereof may be regulated as de-

sired, and will depend upon the size or dimensions of the ship, and by means of my improvement, the chief feature of which is the undulating form of the bulkheads in cross section, I secure the desired strength of the said bulkheads without the necessity of reinforcing or bracing the same in any way, and also secure a certain degree of elasticity in the hull construction which tends to prevent breakage or rupture of the hull in the plane of the transverse bulkheads, the stresses or strains to which the hull is subjected being distributed more or less throughout the hull and being taken up by the vibration of which the bulkheads are capable, and while I have shown the main part of the bulkheads, in Figs. 7, 8 and 9, as of ordinary form, it will be understood that in this construction also the undulating or trough shaped bulkheads may be employed if desired, and my invention is not limited to the exact details of construction herein shown and described and the principle of the construction of bulkheads, or bulkhead frames herein shown and described may be varied, modified or changed in many ways without departing from the spirit of my invention or sacrificing its advantages.

In ordinary cargo ships the application of the bulkhead principle, herein shown and described, will be found of great advantage, in that it reduces or relieves the strain on the hull in the transverse plane of the transverse bulkheads, even when ordinary bulkheads are employed, and while I have shown and described the preferred form of connecting the transverse bulkheads with the bulkhead frames and the transverse bulkheads with the longitudinal fore and aft bulkhead, it will be understood that these features of the construction may also be varied, modified or changed, as experience may prove to be best, and my invention involves, not only the vertical arrangement of the undulations or trough-shaped members of the bulkheads, but also the horizontal arrangement thereof, if such arrangement is found to be advisable.

Having fully described my invention what I claim as new and desire to secure by Letters Patent is:—

1. A bulkhead construction for ships involving a main longitudinal central bulkhead and transverse bulkheads connected therewith and with the sides of the hull by a bulkhead frame construction composed of sheet metal formed into deep undulations or trough-shaped members which open in opposite directions and which are riveted to the hull, and between which and the bulkheads are placed web plates which are riveted thereto and to said bulkheads.

2. A ship the hull of which is provided with bulkheads composed of sheet metal bent to form parallel grooves or trough-shaped

members which open in opposite directions and which are riveted to the deck and to the bottom of the hull and which are connected with the sides of the hull by bulkhead frames composed of sheet metal formed into deep parallel grooves or trough-shaped members, the grooves or members of the frames being at right angles to the grooves or members of the bulkheads, and said frames being riveted to the hull and being also secured to the bulkheads.

3. The herein described bulkheads for ships, said bulkheads comprising a central portion or member and side portions or members, the central portion being corrugated vertically to form deep trough-shaped members which open in opposite directions, and the side portions or members being corrugated horizontally to form deep trough-shaped members which open in opposite directions, said central and side portions being connected by web members riveted thereto, and said side members being secured to the hull of the ship or parts thereof by rivets arranged in continuous S-shaped lines which cross the central plane of the bulkheads.

4. The herein described bulkheads for ships, said bulkheads consisting of sheet metal and being formed from separate trough-shaped members riveted together and which open in opposite directions, said bulkheads also comprising central portions in which the trough-shaped members are arranged vertically, and side portions in which the trough-shaped members are arranged horizontally, said side members being also provided with webs which are secured thereto and to which the central members are secured, and said side members and central members being secured to the hull of the ship or parts thereof by rivets arranged in continuous S-shaped lines which cross the central plane of the bulkheads.

5. A ship provided with bulkheads composed of sheet metal and bent to form deep parallel grooves or trough-shaped members which open in opposite directions and which are secured to the hull by rivets arranged in continuous S-shaped or zig-zag lines which cross the central plane of the bulkheads, said bulkheads being also composed of separate parts which are riveted together and in some of which the grooves or troughs are horizontal and in others vertical.

6. A ship the hull of which is composed of sheet metal and provided with bulkheads also composed of sheet metal, said bulkheads being composed of separate parts formed into deep undulations or trough-shaped members which open in opposite directions, and which abut endwise against the hull of the ship and which are secured thereto by rivets arranged in continuous undulations or S-shaped lines which cross the central plane of the bulkheads.

7. A ship the hull of which is composed of sheet metal and provided with bulkheads also composed of sheet metal, said bulkheads being composed of separate parts formed into deep undulations or trough-shaped members which open in opposite directions, and which abut endwise against the hull of the ship and which are secured to said hull by means of angle bars curved to correspond with the curves of the parts of the bulkheads in cross section, and which are riveted to said parts of the bulkheads, and also secured to the hull by rivets arranged in con-

tinuous undulations or S-shaped curves which correspond with the curves of the said angle bars and which cross the central planes of the bulkheads.

In testimony that I claim the foregoing as my invention I have signed my name in presence of the subscribing witnesses this 20 29th day of June 1912.

SAMUEL HOLMES.
